UNITED STATES PATENT OFFICE.

KARL HÜRTTLE, OF AKRON, OHIO, ASSIGNOR TO LUFTSCHIFFBAU ZEPPELIN GESELLSCHAFT MIT BESCHRANKTER HAFTUNG, OF FRIEDRICHSHAFEN, GERMANY.

GAS-INFLATED AIRSHIP.

Application filed January 30, 1926, Serial No. 84,854, and in Germany February 4, 1925.

My invention relates to gas-inflated airships and more especially to those of the rigid type. Such airships have a shape-giving hull skeleton over which the outer cover is stretched. The space inside is subdivided into compartments into which gas cells are inserted. Due to the stream line shape of the hull the end compartments are comparatively small, so small that it is un-
5 advisable to insert a gas cell which together with its fixtures, valves, sleeves and so on would be so heavy that there would result additional weight instead of additional lift.

My invention improves these circumstances by inserting gas cells without valves and sleeves and by connecting such cells to neighboring bigger cells having valves and sleeves. By this arrangement, I am able to utilize for inflation, relatively small spaces
15 such as the tip ends of the structure, and also the space inside of the fins without materially adding to the weight of the entire ship, but thereby gaining considerably in lift.

20 I prefer to arrange the sleeves which connect a gas cell without valves to one with valves sufficiently high so that the normal gas level will always extend below these sleeves. This will insure a regular state of
25 inflation in the smaller cell.

Having given a general description of my invention, I now want to describe it more in detail referring to the drawings which represent an example embodying my invention.

Fig. 1 is a longitudinal vertical section through the stern of an airship. Fig. 2 is a cross section taken on line 2—2 of Fig. 1. The drawings illustrate the rear portion
40 of a ship and show the hull in a diagrammatical way only. Here there is illustrated a small gas cell 1 at the extreme stern. This cell is not provided with sleeves for inflation or deflation, or with automatic or operated valves, but it has a flue 12 which leads from cell 1 to cell 3. The cell 3 is of ordinary construction and has an inflation valve 6 and a deflation valve 9, which is located at the top of the cell at one side of the top
45 fin 10. The cell 3 also has a valve 4 which

may be controlled in any usual manner and an automatic valve 5. In the two side and top fins 10 are located additional gas cells 7. These, like the cell 1, are not provided with valves, but have flues 8 connecting them with the cell 3. It may be noted that the flues 8 and the flue 12 which connect the cell 3 with the smaller cells are all located at points at least as high as the middle of cell 3. As cell 3 under normal conditions is always maintained at least half full of gas, these connections are above the bottom of the normal gas level.

55 I do not want to limit myself to the details described or shown in the drawings, as many variations will occur to those skilled in the art.

60 What I claim is:

1. An airship comprising a rigid hull, a plurality of individual gas cells inserted into said hull, two adjacent gas cells having a horizontal flue connecting them together, said flue constituting the sole means of communication to the interior of one of the two adjacent gas cells, the other gas cell having 75 gas inlet and outlet fixtures.

2. An airship comprising a rigid hull, a plurality of individual gas cells inserted into said hull, a substantially horizontal flue connecting two adjacent ones of said gas cells, said two gas cells having common gas inlet and outlet fixtures.

3. An airship comprising a rigid hull, a plurality of individual gas cells inserted into said hull, two adjacent gas cells having a horizontal flue connecting them together, said flue constituting the sole means of communication to the interior of one of the two adjacent gas cells, the other gas cell having 85 gas inlet and outlet fixtures, said flue also being situated above the normal high gas level.

4. An airship comprising a rigid hull, a plurality of individual gas cells inserted into said hull, a fin rigidly attached to said hull, a gas cell inserted in said fin, and a flue connecting said gas cell in said fin with one of said gas cells in said hull.

5. An airship comprising a rigid hull, a plurality of individual gas cells inserted into 100

said hull, one of said gas cells being provided with conventional gas inlet and gas outlet fixtures, a second one of said gas cells being without such fixtures, a fin rigidly attached to said hull, a gas cell inserted in said fin, said latter gas cell being without conventional gas inlet and gas outlet fixtures, a flue connecting said first two gas cells with one another, and a flue connecting said gas cell in said fin with said first gas cell having the fixtures, both said flues being situated above the normal high gas level. 10

KARL HÜRTTLE.
